L. H. CARUFEL

STENCIL

Filed Sept. 22, 1923

INVENTOR.

L. H. Carufel

BY
Watson E. Coleman
ATTORNEY.

UNITED STATES PATENT OFFICE.

LOUIS H. CARUFEL, OF MINNEAPOLIS, MINNESOTA.

STENCIL.

Application filed September 22, 1923. Serial No. 664,217.

To all whom it may concern:

Be it known that I, LOUIS H. CARUFEL, a citizen of the United States, residing at Minneapolis, in the county of Hennepin and State of Minnesota, have invented certain new and useful Improvements in Stencils, of which the following is a specification, reference being had to the accompanying drawings.

10 This invention relates to certain improvements in stencils and has relation more particularly to a device of this general character especially designed and adapted for use in connection with the cutting of glass with a sand-blast and it is an object of the invention to provide a device of this general character having novel and improved means whereby the same may be properly positioned upon the work.

15 Another object of the invention is to provide a novel and improved device of this general character whereby varying areas may be properly treated with a sand-blast together with means whereby a sand-blast 25 may be employed for producing a suitable symbol upon the glass.

The invention consists in the details of construction and in the combination and arrangement of the several parts of my improved stencil whereby certain important 30 advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

40 Figure 1 is a view in top plan illustrating a stencil constructed in accordance with an embodiment of my invention and in applied position, the same being assembled for use for the production of a symbol.

45 Figure 2 is a sectional view taken substantially on the line 2—2 of Figure 1;

Figure 3 is a sectional view taken substantially on the line 3—3 of Figure 1;

50 Figure 4 is a sectional view taken through the device with the removable rings omitted;

Figure 5 is a sectional view taken through a removable ring adapted for use in connection with the structure illustrated in Figure 4.

As disclosed in the accompanying draw-

ings, 1 denotes an annular member of suitable material, preferably rubber, providing a central opening 2 of a relatively large diameter. The member 1 is broad and has 60 its opposed faces flat whereby the same may be readily applied to the surface of a glass plate P.

Cemented or otherwise secured to the inner marginal portion of the member 1 is 65 an annular member 3 preferably of metal, the inner marginal portion of said member 3 overlying the central opening 2 of the member 1.

An annular member 4 is adapted to be 70 snugly fitted within the opening 2 of the member 1, said member 4 being of substantially the same thickness as the member 1. With the member 4 in applied position the member 3 serves to maintain the member 4 75 in proper position upon the plate P. When it is desired to cut a hole through the plate P, a member 4 is operatively engaged with the member 1 having a central opening 5 of a diameter in accordance with the size of 80 the opening desired to be produced in the plate P.

After the assembled members 1 and 4 have been properly positioned upon the plate P the same are held in such position through 85 the instrumentality of suitable clamps 6, said clamps preferably having direct contact with the member 3.

It is to be understood that my improved stencil is adapted for use in connection with 90 a sand-blast in a manner commonly employed in the cutting of glass and when so used the close contact of the members 1 and 4 with the plate P assures the proper cutting 95 action of the blast upon the glass.

When it is desired to produce a symbol upon the surface of the glass, the required member 4 is applied to the member 1 and within the central opening 5 of such applied member 4 is suitably arranged the supplemental stencil S cut in accordance with the design desired, the opposed portions of said stencil S and the member 4 having coacting therewith the bridge pieces 7 for maintaining the supplemental stencil S in desired position.

The stencil S is also preferably formed of rubber and when it is required to initially produce said stencil in separable parts in order to produce the desired lines, the adjacent parts of such stencil are also connected by a suitable bridge piece, as indicated at 8.

From the foregoing description it is thought to be obvious that a stencil constructed in accordance with my invention is particularly well adapted for use by reason 5 of the convenience and facility with which it may be assembled and operated, and it will also be obvious that my invention is susceptible of some change and modification without departing from the principles and 10 spirit thereof and for this reason I do not wish to be understood as limiting myself to the precise arrangement and formation of the several parts herein shown in carrying out my invention in practice except as hereinafter claimed.

I claim:—

1. A device of the class described comprising a strip of material defining an opening, a member carried by the strip and partially 20 overlying the central opening defined by the strip, and a separable member defining an

opening, said member being snugly insertible within the opening defined by the strip, the strip and second member being of yieldable material and coplanar when in assembled relation. 25

2. A device of the class described comprising a strip of material defining an opening, a member carried by the strip and partially overlying the central opening defined by the strip, a separable member defining an opening, said member being snugly insertible within the opening defined by the strip, said strip and separable member being coplanar when in assembled relation, and a stencil 30 adapted to be positioned within the opening defined by the first named member, said stencil being of yieldable material. 35

In testimony whereof I hereunto affix my signature.

LOUIS H. CARUFEL.
